(57) **CLAIM**

The ornamental design for a display screen with animated graphical user interface, as shown and described.

DESCRIPTION

The file of this patent contains at least one drawing/photograph executed in color. Copies of this patent with colored drawing(s)/photograph(s) will be provided by the Office upon request and payment of the necessary fee.

FIG. 1 is a front view of a first image in a sequence of images of an animated display screen with animated graphical user interface;

FIG. 2 is a front view of a second image of the sequence of images of the animated graphical user interface illustrated in FIG. 1;

FIG. 3 is a front view of a first image in a sequence of images of a second embodiment of an animated display screen with animated graphical user interface; and,

FIG. 4 is a front view of a second image of the sequence of images of the animated graphical user interface illustrated in FIG. 3.

The outermost broken line showing of a display screen and the other broken line showing of elements of the graphical user interface illustrate portions of the article and do not form part of the claimed design.

The appearance of the animated graphical user interface transitions sequentially between the images shown in FIGS. 1 and 2 in embodiment 1 and FIGS. 3 and 4 in embodiment 2. The process or period in which one image transitions to another forms no part of the claimed design.

FIG. 2

The screenshot shows a mobile application interface for managing financial positions. The title 'POSITIONS' is at the top, with a three-line menu icon to its left. Below the title is a search bar with the placeholder 'FILTER BY ACCOUNT' and a 'All' button with arrows. A navigation bar below the search bar has two tabs: 'by Account' (selected, highlighted with a dotted background) and 'by Instrument'. The main content area is a table with columns: 'PRODUCT', 'NET', and 'P/L'. The table lists the following positions:
